PROCESS FOR PREPARING HYDROCARBONS
FOR POLYMERIZATIONHarrison L. Hays, Phillips, and Joseph L. Maher,
Odessa, Tex., assignors to Phillips Petroleum
Company, a corporation of Delaware.

Application May 20, 1940, Serial No. 336,250

6 Claims. (Cl. 260—683.1)

This invention relates to the manufacture of hydrocarbons from hydrocarbons having lower molecular weights and in particular it relates to the manufacture of normally liquid hydrocarbons from normally gaseous paraffins. More specifically it deals with the production of a suitable charge stock for a subsequent polymerization step which may be either catalytic or thermal. This charge stock is prepared from a hydrocarbon conversion process which may be one either of dehydrogenation of gaseous paraffins or of thermal treatment of higher-molecular-weight hydrocarbons whereby normally gaseous olefins and paraffins together with hydrogen are formed. This separation is aided by a unique application of a particular stream of unreacted recycle olefins which have been separated from the effluent of an olefin-polymerization step.

It has been shown that, when used as fuel for internal-combustion engines, especially those of the spark-ignition type, various hydrocarbons have widely different combustion and detonation characteristics. Thus, in general, olefin hydrocarbons are less likely to produce or cause detonation when used as a fuel than are the corresponding paraffin hydrocarbons. Even among one given class of hydrocarbons, such as the paraffins, for example, the various individual hydrocarbons differ widely among themselves as to their combustion characteristics. This is exemplified by the detonation characteristics of normal heptane and of isoctane (2,2,4-trimethylpentane), the well-known standards used for evaluating detonation; the first causing detonation to a considerable extent and has, by definition, a rating of zero octane number, and the latter causes little if any detonation, even in engines having relatively high compression ratios, and has by definition a rating of 100 octane number. Even hydrocarbons belonging to the same class and having the same molecular weights have widely different detonation characteristics, as exemplified by various heptanes, whose octane numbers are as follows:

Hydrocarbon	Octane number
Normal heptane.....	0
2-methyl hexane.....	55
3-methyl hexane.....	65
2,2-dimethyl pentane.....	80
2,3-dimethyl pentane.....	92
2,4-dimethyl pentane.....	80
3,3-dimethyl pentane.....	98
2,2,3-trimethyl butane.....	116
3-ethyl pentane.....	68

There is considerable advantage to be gained from using fuels with good antidentalating qualities, inasmuch as only fuels which can be so classified can be used in engines with high compression

ratios. It is well known that it is possible to obtain a high thermal efficiency in such an engine, and it has been found that the potential power to be obtained using an engine operating, in each case, at the highest permissible compression ratio, may be 50 percent greater with a given hydrocarbon with high antidentalating qualities as a fuel than when using an isomeric hydrocarbon with lower antidentalating qualities. As an example, the maximum possible compression ratio of an engine using normal heptane as a fuel is about 3:1, while with its isomer, 2,3,3-trimethyl butane, the maximum ratio is about 13:1. An engine with the latter compression ratio would actually not operate if normal heptane were the fuel.

In the preparation of such premium motor fuel, especially when catalytic polymerization is used, it is generally preferable to prepare a charge stock for such polymerization which contains predominantly C₃ and C₄ hydrocarbons with very little lighter material present. Under ordinary conditions of operation the presence of very much material lighter than C₃ hydrocarbons is quite deleterious, in that it is generally the practice to pump such charge stock in the liquid state and if such material is present in very large amounts the pump will not operate very satisfactorily. Also ethylene is not very readily reacted in the presence of a catalyst under the operating conditions which are most favorable for the production of simple olefin polymers, although it is a very desirable material to have in several conversion operations, such as thermal alkylation.

We have found that a normally gaseous hydrocarbon mixture which contains hydrocarbons lighter than C₃ hydrocarbons in addition to desirable C₃ and C₄ hydrocarbons, may be readily freed of these lighter hydrocarbons by passing such a mixture to a fractionating column, and by cooling the top of this column by the refrigeration effect produced by the vaporization of unreacted light hydrocarbons which have been separated from the polymerization effluent. Thus, in the operation of our process in its most simple form, a hydrocarbon mixture comprising olefin hydrocarbons derived from a previous hydrocarbon conversion process and containing predominant amounts of C₃ and C₄ hydrocarbons, along with smaller amounts of undesirable lighter material, is introduced substantially in the liquid phase into the middle portion of a fractionating column. A suitable polymerization or olefin conversion charge stock containing these desirable C₃ and C₄ hydrocarbons, and substantially free of the undesirable lighter material, is withdrawn from a low point in the fractionating column and is passed to an olefin conversion process wherein the olefin hydrocarbons are converted into higher-boiling hydrocarbons. The effluent of this conversion process is sent to separating means. The lighter

portion of the unconverted hydrocarbons is separated from this effluent and is passed in the liquid phase as a refrigerant in heat-exchange relationship with vapors being evolved from the top of the fractionating column from which the charge to the olefin conversion process has been drawn.

As is more fully brought out hereinafter, this heat-exchange relationship between the recycled lighter hydrocarbons and the vaporous material passing from the top of the fractionating column may be either a direct or indirect relationship. In the polymerization process described by Frederick E. Frey in his application Serial No. 305,549, filed November 21, 1939 a direct heat-exchange relationship is especially applicable, since the recycled hydrocarbons contain polymerizable olefins, such as propene, which are to be recycled to the polymerization step. In the practice of this modification of our invention, this unreacted material serves a cooperative dual function, that is, as a direct-contact refrigerant and reflux, and as a recycle of unreacted olefins to an olefin-polymerization step.

It is an object of this invention to provide a process for the production of a suitable charge stock for a conversion process for the production of normally liquid hydrocarbons from normally gaseous hydrocarbons.

It is another object of this invention to provide a process for the production of, from a normally gaseous hydrocarbon mixture containing undesirable low-boiling material, of a hydrocarbon fraction which is free of that undesirable low-boiling material and which is suitable for a subsequent conversion process to form hydrocarbons having higher molecular weights.

Another object of this invention is to provide a process for the utilization of hydrocarbon material available in the effluent of an olefin-polymerization process to aid in the preparation of a suitable feed stock for the polymerization process.

Further objects and advantages of this invention will be apparent from the following description and disclosure.

In one method for practicing the process of our invention, it is preferred to produce a charge stock for a catalytic polymerization step from the effluent of a step which involves the dehydrogenation of a mixture of butane, preferably of a mixture which contains predominantly isobutane. With such a mixture, which is predominantly isobutane, thermal dehydrogenation is a very satisfactory method of producing suitable olefins for subsequent catalytic polymerization; such an operation does not involve the great expense which is attached to a catalytic dehydrogenation operation. The olefins produced by such a step consist primarily of propene and isobutane, with only minor amounts of other hydrocarbons, as well as methane, which is present in an amount substantially equivalent to the propene, and unreacted isobutane and hydrogen. From the effluent of this dehydrogenation, the hydrogen and methane may be substantially completely removed by a separation which involves only compression to a pressure between about 100 to 500 pounds per square inch and subsequent cooling. The liquid produced by such a separation will contain only small amounts of material lighter than C₃ hydrocarbons, but in amounts in excess of that desirable for the subsequent polymerization step. Such a liquid is passed to the mid-section of a fractionating column which is suitably heated at the bottom. From the bottom of the fractionating column a suitable hydrocarbon mixture can

be separated and passed to a polymerization step. The effluent of this polymerization step will contain appreciable amounts of unreacted C₃ hydrocarbons, a portion of which will be propene, as well as unreacted C₄ hydrocarbons, which will be predominantly butane. This will be especially true after the operation of the entire process has reached a steady state with suitable recycle of the C₃ hydrocarbons, as is hereinafter described.

10 These unreacted C₃ hydrocarbons are separated from the polymerization effluent and are passed, as a liquid, directly to the top of the fractionating column, wherein they are vaporized to a substantial extent and act as a direct-contact refrigerant and liquid-absorption medium. C₃ hydrocarbons which are not so vaporized pass down the column in the liquid state and are subsequently removed from the bottom of the column with the liquid hydrocarbon fraction which is passed to the polymerization step.

20 It is, therefore, readily seen that even should this C₃ hydrocarbon fraction consist primarily only of propene, as described by Frey in his aforementioned application, Serial No. 305,549, 25 the amount of this C₃ hydrocarbon fraction will increase as the polymerization operation reaches a steady state and there will be ample material available to enable the fractionating column to operate satisfactorily. In the event, however, 30 that this C₃ hydrocarbon fraction consists predominantly of propane, in one modification of the present process, this material may be used as an indirect-contact refrigerant, as is more fully described hereinafter, the desired refrigerating 35 effect being produced without introducing it directly into the fractionating column.

Our invention will now be described in connection with Figures 1 and 2 of the accompanying drawings which form a part of this specification.

Figure 1 shows diagrammatically one arrangement of an apparatus suitable for practicing our invention.

Figure 2 shows diagrammatically a modification of certain parts of the apparatus shown in Figure 1. Only a part of the apparatus shown in Figure 1 is reproduced in Figure 2 and the various units thereof are designated by the same reference numerals as are used in Figure 1.

40 A hydrocarbon stream comprising a butane, and which may comprise essentially pure isobutane, enters the system through conduit 10, and is compressed to a suitable pressure by pump 11. In many cases where such a butane stream comes directly from a fractional distillation, or other separation step, it may be under a pressure sufficiently high so that the pump 11 will not be necessary and in such cases this pump may, of course, be omitted. Since a high superatmospheric pressure tends to affect the subsequent dehydrogenation adversely, the pressure should be generally only sufficient to overcome the pressure drop through the apparatus up to the compressor 41, and to provide a slight superatmospheric pressure at the inlet to the compressor. Such a pressure will not need to be in excess of about 200 pounds per square inch and will generally be considerably less than that.

45 The butane stream, at a desired pressure, then passes through a conduit 12, and through conduit 13 supplied with valve 14, to the transfer line heat exchanger 15, where it passes in indirect countercurrent heat-exchange relationship with the effluent of the dehydrogenation to be described. From the heat exchanger 15, the

stream passes through conduit 16, which is controlled by a valve 17, to conduit 18, and on to the dehydrogenation step. With this arrangement, valve 21 in the by-pass 22 is closed, but if desired, all or any part of the stream may be diverted from the heat exchanger 15 through this by-pass by proper control of the valves 14, 17, and 21, as will be obvious to those skilled in the art. From the conduit 18 the stream passes through the coil 23 located in the furnace 24. When the dehydrogenation step is so operated that complete thermal dehydrogenation of the hydrocarbon stream is accomplished, that is to say, substantially no catalytic dehydrogenation takes place, these coils will be of such dimensions that the hydrocarbon stream is heated rapidly to a dehydrogenating temperature of the order of 1000 to 1250° F., and is held within this temperature range for a period of time such that between about 10 and 40 mol percent of the effluent material consists of normally gaseous olefin hydrocarbons. With such a procedure the effluent of the coil 23 passes through conduit 25, which is controlled by a valve 26, and sent through heat exchanger 15, conduit 27, cooler 28, and conduit 30 to the scrubber 31. When it is desired to carry out a catalytic dehydrogenation, this may be done by opening valve 32 in conduit 33 and valve 34 in conduit 35, thus connecting catalyst chambers 36 into the system, and closing the valve 26.

In the modification illustrated in Figure 1, the catalyst chambers 36 comprise relatively small tubes filled with a suitable dehydrogenation catalyst and are so arranged that large amounts of hot combustion gases pass over them. With such a modification the relative volume of the coils 23 is such that the hydrocarbon stream is rapidly heated to a desirable reaction temperature, such as between about 850 and about 1150° F., and the stream is then passed directly into contact with the dehydrogenation catalyst in the tubes of chambers 36. As the dehydrogenation reaction progresses, heat is absorbed and this is made up by heat transfer from the combustion gases surrounding these catalyst tubes. Although only one source of heat in the furnace 24 is shown, it will be understood that additional burners, or other sources of heat solely for supplying heat to the catalyst tubes and the reactions at the desired temperature level, may also be used. The dehydrogenation effluent passes from the catalyst chambers 36 through conduit 35, which is controlled by valve 34, and is sent through conduit 25 and heat-exchanger 15 to the remainder of the apparatus as has been hereinbefore and is hereinafter described.

If desired, a further modification may be used, wherein a part of the desired dehydrogenation may be effected by thermal means in the coils 23 and a subsequent amount of the controlled desired dehydrogenation may be effected by the dehydrogenation catalyst.

In the scrubber 31, carbon and/or tar is separated from the stream and removed through conduit 37, controlled by valve 38. However, it has been found that with suitably controlled dehydrogenation conditions there is little if any of such heavier materials formed, and in such cases there will be no such material to be removed by the scrubber. In such cases the scrubber 31 will only be included as a precautionary measure. However, if such material is present, this removal may be aided by the use of a heavy absorption oil or other means, introduced to 75

scrubber 31 through valved line 39 as will be evident to those skilled in the art, and details pertinent to this modification have not been shown. The effluent of the dehydrogenation step passes from scrubber 31 through a conduit 40 to a compressor 41, which compresses this stream to a pressure of between about 75 and 175 pounds per square inch. The compressed stream passes through conduit 42 to a cooler and condenser 43, and then through conduit 44 to a vapor-liquid separator 45.

Under the pressure developed by compressor 41 and at the temperature effected by the cooler and condenser 43, all of the hydrocarbon material having four carbon atoms per molecule, along with an appreciable proportion of the propane and lighter hydrocarbons, will be condensed and may be removed from the following separator 45 as a liquid stream. This liquid hydrocarbon mixture will also contain a certain amount of undesirable light material, and therefore it is passed from the separator 45 through a conduit 46, controlled by the valve 47, to the fractionating column or poly-feed stripper 50. Gaseous material which has not been condensed to a liquid under conditions which are present in the separator 45, passes therefrom in the gaseous stage through conduit 120 controlled by a valve 121.

If desired, a mixture having a composition similar to that in conduit 46 may be introduced to the system through conduit 48 controlled by a valve 49, and leading into conduit 46. At times, all of the charge stock to the process may be introduced through conduit 49. In such a case, the dehydrogenation step, if used, will operate only on hydrocarbons which pass through conduit 93, as hereinafter described.

The fractionating column or poly-feed stripper 50 generally operates under a pressure slightly lower than that existing in the separator 45, such as a pressure of about 50 to 175 pounds per square inch, and in such a case an intermediate pump will not be necessary. In some cases it may be desirable to operate the fractionating column 50 at a somewhat higher pressure, such as up to about 300 pounds per square inch, and in such a case a suitable pump may be inserted in the conduit 46, as will be readily understood. The most economical operation has been found to be obtained between 75 and 200 pounds per square inch.

When the compression produced by compressor 41 is not sufficient to produce a separation of liquid in separator 45, the charge to fractionator 50 may be withdrawn from conduit 127 through conduit 129 and valve 139 which leads to conduit 46, and fractionator 50 will operate above the pressure developed by pump 41. If, when such a procedure is followed, a small amount of liquid does separate in separator 45, it may be removed through conduit 46 and compressed by a pump, not shown, inserted in 46 ahead of the juncture of conduit 129, as will be readily appreciated.

The stripper or separator 50 comprises essentially a conventional bubble-plate fractionating column which is heated at the bottom by a conventional heating means such as a heating coil 51. The top of the fractionating column is cooled by the vaporization and expansion of a low-boiling hydrocarbon material in the liquid phase which has been separated from a subsequent polymerization step. Such liquid hydrocarbon material, which, in the present instance, may comprise substantially C₃ hydrocarbons, passes from

the accumulator 52 through a conduit 53, controlled by valve 54, to a pump 56, and is sent through conduit 57, controlled by a valve 58, to be used as a refrigerant for cooling the top part of the fractionating column. As one method of operation, this liquid stream of light, unreacted hydrocarbon material may be introduced directly into the top of the separator or fractionating column system, as by means of an expander and spray nozzle 60, as shown, or by any other means known to the art. When this is done, a considerable amount of the stream is vaporized, producing a large refrigeration effect which is quite efficient by reason of the direct heat exchange which can be had with the vapor present in the column at that point. Heavier constituents of these vapors are condensed to liquid as a result of this refrigeration, and are directly returned to the column along with unvaporized portions of the stream entering through conduit 57. It will be understood that fractionating column 50 is of a conventional type, with suitable bubble trays or the like, not shown, and operates with a countercurrent flow of vapors and liquid throughout the column.

Uncondensed vapors which comprise light hydrocarbons, a small amount of hydrogen which was dissolved in the hydrocarbon stream passing through conduit 46, vaporized light hydrocarbon, such as C₃ hydrocarbons which were introduced through conduit 51, and only small amounts of heavier hydrocarbons pass from the fractionating column 50 through conduit 61, controlled by a valve 62, and are mixed with the vapors passing from separator 45 through conduit 120. When the charge to fractionator 58 comes principally from the bottom of separator 126 through conduit 128, these vapors passing from the top of fractionating column 50 may be passed from conduit 61 through conduit 63 and valve 64 and introduced into conduit 128. Some of the unvaporized propene and propane, introduced as a refrigerant and reflux when direct cooling by the C₃ stream is used, remains as a liquid and is finally removed from a low portion of the fractionating column along with butene and heavier hydrocarbons and these pass through conduit 65, controlled by a valve 66, and through a pump 67 to means for converting these C₃ and C₄ hydrocarbons to normally liquid hydrocarbons, such as the polymerization chamber 70 shown.

The conversion process is most preferably one of catalytic polymerization, carried out at a pressure between about 50 and 2000 or more pounds per square inch, at a temperature between about 75 and 500° F., but it may also be a thermal polymerization process operating within a temperature range within about 700 to 1100° F. under pressures between 500 and 2500 pounds per square inch or more, as may be desired and permitted by the materials going into the construction of the conversion apparatus. The effluent of this conversion passes from chamber or converting means 70 through a conduit 71, controlled by a valve 72, to a polymer separator 73, which is provided with a suitable heating coil 74 at the bottom and a suitable cooling means 75 at the top and supplied with suitable bubble trays or the like, not shown. Polymers produced by conversion means 70 are removed from a low part of this fractionating column through a conduit 76 controlled by a valve 77, and may be subsequently further fractionated and otherwise treated, as may be found most desirable. Lighter

hydrocarbon material, which will comprise mainly hydrocarbons having four carbon atoms per molecule and less, passes from polymer separator 73 through conduit 80 controlled by a valve 81, cooler 82, conduit 83, pump 84 and conduit 85 to further separating means such as the depropanizer 86. This depropanizer is supplied with suitable heating means for the bottom, represented by the coil 87, and suitable cooling means for the top, represented by the cooling coil 88. Hydrocarbons comprising four and more carbon atoms per molecule are removed from the bottom of this depropanizer 86 by means of a conduit 89, controlled by a valve 91, and may be removed from the process through valve 92; or any part or all of this hydrocarbon mixture may be reintroduced into the dehydrogenation process by passing it from conduit 89 through conduit 93, controlled by a valve 94, with suitable control of the valve 92.

Vaporous hydrocarbons, such as a substantially C₂ hydrocarbon mixture, pass from the separator 86 through a conduit 95, controlled by a valve 96, and are sent through valve 97 and cooler 98 to the accumulator 52 by means of conduit 99. Any part or all of this fraction may be discharged from the process by means of conduit 100 controlled by a valve 101. In cases where this hydrocarbon fraction has a high content of paraffin hydrocarbon and it is desired to recycle a hydrocarbon mixture which is more rich in olefin hydrocarbon, the fraction passing from separator 86 by means of conduit 95 and 100 may be subjected to some sort of olefin concentration procedure, which is not shown but which is well known to those skilled in the art, and a more highly concentrated olefin-containing fraction may be reintroduced into the process as a liquid to conduit 102, controlled by a valve 103, and leading into conduit 53. The accumulator 52 is provided with a suitable vent 105 provided with a valve 106, through which unreactive vapors and gases may be vented from time to time, or continuously, as may be found desirable.

The material passing as a gas or a vapor from separator 45 through conduit 126, controlled by a valve 121, contains hydrogen produced in the dehydrogenation step along with some methane and other light hydrocarbons and also along with some of the heavier, normally gaseous hydrocarbons, such as propene and butene, which it is desired to incorporate as a part of the charge stock to the polymerization step just described. To this material is added vapors from the fractionating column 50 passing through conduit 61, and the resultant mixture is compressed by a compressor 122 and passes through conduit 123, cooler 124, and conduit 125 to another vapor-liquid separator 126. Higher-boiling portions of the mixture originally passing as a gas through conduit 126 and 61 will be in a liquid state after this compression and cooling, and are separated in separator 126 from uncondensed gases and vapors. This liquid material contains appreciable quantities of propene and butene and is removed from separator 126 through a conduit 127, controlled by a valve 128, and is introduced into conduit 44 to be reintroduced into the separator 45.

Uncondensed material passes from the separator 126 through a conduit 129, controlled by a valve 131, to a compressor 132, then through conduit 133, cooler 134, and conduit 135 to another vapor-liquid separator 136. The separator 136 is operated at a pressure between about

300 and 850 pounds per square inch and, preferably, in the range of 500 to 750 pounds per square inch. Higher-boiling constituents of the vapors passing from separator 126 to conduit 130 are liquefied by this compression and cooling step, and are removed from separator 136 through a conduit 137, controlled by valve 138, and are reintroduced into conduit 125 and separator 126. The material which remains uncondensed in separator 136 now comprises an appreciable concentration of hydrogen and methane and contains only small amounts of heavier hydrocarbons. It will, however, contain an appreciable proportion of propene and butene, which should be recovered. This fraction passes from separator 136 through a conduit 140 controlled by a valve 141 to an absorber 150.

In the absorber 150 the gaseous material which is passed from the separator 136, and which is now at an elevated pressure of the order of about 750 pounds per square inch, more or less, is contacted with the lean absorption oil introduced at the top of the absorber through conduit 165. This absorption oil is introduced in such amounts that essentially all the hydrocarbons having three and more carbon atoms per molecule, which are present in the material passing through conduit 140, are absorbed along with much of the lighter hydrocarbon material. The residue gas, containing principally hydrogen and methane, passes from the absorber 150 through conduit 151. The rich absorption oil passes from the absorber 150 through conduit 152, controlled by valve 153, to heater 154, and is sent through conduit 155 to the top of the stripper 156, which it enters at a low pressure, of the order of about 10 to 50 pounds per square inch, and at an elevated temperature, which need not be in excess of about 225 to 250° F. In the stripper 156 the light hydrocarbons which have been absorbed by the oil in absorber 150 are removed as a vapor from the absorption oil. The denuded absorption oil passes from the bottom of the stripper through conduit 157 controlled by a valve 158, through cooler 159 and then through conduit 160 to an accumulator 161. From the accumulator 161 the absorption oil is removed through conduit 162, controlled by a valve 163, and is pumped by a pump 164 through a conduit 165, controlled by a valve 166, to the top of the absorber 150.

Lean residue gases passing from the absorber 150 through conduit 151 may be discharged from the system through valve 170, or a part of these gases may be diverted from conduit 151 through conduit 171, controlled by a valve 172, to the bottom of the stripper 156, where they are introduced to the stripper to aid in stripping the remaining amount of absorbed hydrocarbons from the oil just before it leaves the stripper through conduit 157. A gaseous material passes from the top of the stripper 156 through a conduit 173, controlled by a valve 174, and finally is reintroduced into the system through valve 175 into conduit 30, where it is mixed with the effluent of the dehydrogenation operation.

In Figure 2 is shown a modified arrangement of apparatus whereby our process may be practiced by using an indirect heat-exchange relationship between the light liquefied hydrocarbons, which are used as a refrigerant, and the vapors passing from the top of the fractionating column or poly-feed stripper 50. This modification is shown only with such necessary parts of the arrangement of apparatus shown in Fig-

ure 1 as to show the inter-connection clearly, and for these parts the same numerals have been used to indicate the same pieces of apparatus.

As was described in connection with the apparatus shown in Figure 1, a liquid hydrocarbon mixture containing C₃ and heavier hydrocarbons, together with some lower-boiling material passes from the separator 45 through conduit 46, controlled by a valve 47, to a fractionating column 50. This fractionating column is supplied with suitable heating means, such as the heating coil 51 in the bottom, and a liquid charge stock suitable for the subsequent polymerization step is drawn from the fractionating column 50 through a conduit 65 controlled by a valve 66. Low-boiling material in the gaseous phase passes from the top of the fractionating column 50 through conduit 200 to cooler and condenser 201, wherein it is cooled to a temperature sufficiently low to condense most of the C₄ and heavier hydrocarbon material, and some of the C₃ hydrocarbons. The cooled mixture passes from the cooler and condenser 201 through conduit 202 to the accumulator and surge tank 203. A stream of low-boiling unreacted hydrocarbons, such as C₃ hydrocarbons, is withdrawn in the liquid phase from the accumulator 52 through conduit 53, controlled by a valve 54, and is passed by pump 56 through conduit 57, and the expansion valve 58 to the cooler and condenser 201. If desired, or necessary, some sort of cooling means may be interposed in conduit 57 subsequent to the pump 56, and with this modification it may at times be possible to operate without the use of the pump 56 which may be by-passed by means not shown. In the cooler and condenser 201 this liquid hydrocarbon stream is partially or completely vaporized and produces thereby an appreciable cooling and refrigerating effect. This vaporizing material is in indirect heat-exchange relationship with vapors passing from the top of the fractionating column 50 through conduit 200, as will be readily appreciated by those skilled in the art.

The expanded material passes from the cooler and condenser 201 through conduit 210, and passes through valve 211 to conduit 44 and is reintroduced into the system. If desired, any part or all of the vaporized stream may be passed from conduit 210 through conduit 212, controlled by a valve 213, valve 211 being closed or partly closed, as the method of operation may require. A part or all of the material used as a refrigerant may be introduced to conduit 53 through conduit 102 controlled by a valve 103. Material which has passed from the top of the fractionating column 50 and which has been liquefied in the cooler and condenser 201, will accumulate at the bottom of the accumulator 203 and may be passed back to the fractionating column 50 through conduit 204, controlled by a valve 205, being pumped by pump 206 through conduit 207 to the top portion of the fractionating column 50. Uncondensed material will be passed from the top of the accumulator 203 to a conduit 61, controlled by a valve 62, and will be passed into the conduit 120, which contains gaseous material passing from the separator 45, as has been described hereinbefore in connection with Figure 1. The remainder of the apparatus is the same as has been hereinbefore described in connection with Figure 1.

The operation of this modification of our process does not produce results which are markedly different from the results produced when the

first described modification is used. However, it does permit the advantageous use of the light unreacted hydrocarbons as a refrigerant in preparing a charge stock, or a subsequent conversion process without mixing this refrigerating material with the charge stock. While in many operations to which our invention may be adapted, it will be desirable to incorporate the material which makes up this refrigerant as a part of the charge stock to a conversion process, it may also often be desirable to secure the refrigerating effect of all of the stream before it is subjected to subsequent treatment. Thus, in the event that the light unreacted material is largely paraffinic, it may be successfully used in the modification shown in Figure 2 as a refrigerant and then can be passed from the system through conduit 212. If it is desired to recirculate this material to the process, it may then be passed to the dehydrogenation step, along with fresh charge stock which enters the system through conduit 10. In case this material contains an appreciable amount of olefin hydrocarbons, but too large an amount of paraffin hydrocarbons to make it desirable to introduce the stream directly to the polymerization process, the material which is passed from the system through conduit 212 may be sent to olefin-paraffin separation means not shown, and the olefins separated from the paraffins and returned to the process through conduit 49, while the paraffins are mixed with fresh charge and introduced to the process through conduit 10.

The dehydrogenation step of the process may be either thermal or catalytic or a combination of both, but in any case it should be conducted at as low a pressure as will be practicable. Although a subatmospheric pressure may at times be most desirable, it will generally be more practicable to operate this step at a superatmospheric pressure which, however, should not exceed about 200 pounds per square inch and should be preferably only sufficiently high to insure adequate flow through the apparatus and provide a small superatmospheric pressure at the inlet to the compressor 41. When pressures near the upper part of this range exist in the tar separator 31 and when the cooler 43 may be operated at a low temperature, such as a temperature of about 35° F. or even less, it may be possible to do away with the compressor 41, as will be appreciated by those skilled in the art.

The dehydrogenation catalyst, when one is used, will preferably be of the chromium oxide type, such as those disclosed in U. S. Patents 1,905,383 and 2,098,959 (Re. 21,911), and in the copending application of Matuszak and Morey, filed November 9, 1937, Serial Number 173,708, now Patent 2,294,414, granted September 1, 1942, or of the bauxite type, such as those disclosed in the copending application of Schulze, filed October 6, 1936, Serial Number 104,306, now Patent 2,167,602, granted July 25, 1939. With such dehydrogenation catalysts, the dehydrogenation temperature may be as low as about 750° F. but generally somewhat higher dehydrogenation temperatures, such as those of the order of about 850 to 1150° F., will produce the most desirable results.

If thermal dehydrogenation is to be employed, somewhat higher temperatures, such as up to about 1300° F., should be used, with a preferred range for thermal dehydrogenation lying between about 1000 and 1250° F. In any event, the reaction time should be such that between about 10

and 40 mol per cent of the effluent consists of catalytically polymerizable olefins, and preferably about 20 mol per cent of such olefins, in order that secondary reactions of the dehydrogenation products do not take place to any appreciable extent in the dehydrogenating portion of the apparatus.

As has been mentioned hereinbefore, the polymerization which will take place in the apparatus diagrammatically represented as the catalytic polymerization chamber 18, may actually be either a thermal or catalytic process and may involve not only the polymerization of olefin hydrocarbons, but may also be operated to include in any known manner the reaction of olefin hydrocarbons with other hydrocarbons, such as paraffins, naphthenes, and aromatics, to produce desired hydrocarbons of higher molecular weights. One very advantageous manner of operating this part of the process has been described by Frederick E. Frey in his copending application Serial Number 305,549, filed November 21, 1939. In this modification, the hydrocarbon stream which passes from the fractionating column 50 to the conduit 65 contains substantially only propene and butene as the olefins to be reacted, and the polymerization is so operated that substantially all of the butenes are polymerized along with only a portion of the propene which is present. With this modification the hydrocarbon stream passing from the top of the fractionating column 86 through conduit 95 contains propene in high concentration, with some propane being substantially the only other hydrocarbon present. When this is the case, the modification of apparatus shown in Figure 1 may be used, where this stream is introduced directly into the top of fractionating column 50, as has been described.

In modifications of the polymerization step, 40 wherein substantially all the light olefins such as propene are polymerized, and only the corresponding paraffins remain, it will generally be more desirable to use an indirect method of cooling for the top of the fractionating column 50 as has been described herein in connection with the modification shown in Figure 2. This may also be true in connection with a process wherein the polymerization step is a thermal one, although in this case the direct refrigeration shown in Figure 1 may be used, even though the hydrocarbon stream used as a refrigerant may have a low olefin hydrocarbon content.

As an example of the operation of one modification of our process, a hydrocarbon mixture comprising substantially pure isobutane, along with not more than about 10 per cent of normal butane, was mixed with about 2½ times as much recycled hydrocarbon material having substantially the same composition, and this mixture was passed through the thermal dehydrogenation coils 23, the catalyst chamber 36 not being in operation at this time. A dehydrogenation temperature in the coils 23 was maintained between about 1150 and 1220° F. and a gage pressure of about 25 pounds per square inch was maintained at the exit of the dehydrogenation apparatus. The effluent of the dehydrogenation contained about 11 per cent isobutene and other butenes and about 8 per cent propene, about 8½ per cent hydrogen and a little over 12 per cent methane, the remainder being unreacted butane. This material was compressed to a pressure of about 130 pounds per square inch and was passed at a temperature of about 85° F. to the vapor-liquid separator 45. The condensed liquid, which con-

tained about 3 per cent of material lower-boiling than C₃ hydrocarbons, was passed from the separator 45 through the conduit 46 to a fractionating column 50 which was operated at a pressure of about 120 pounds per square inch. The bottom of the fractionating column was maintained at a temperature of about 105° F. by means of the heating coil 51 and the top was cooled to a temperature of about 60° F. by an introduction and vaporization of a substantially pure C₃ hydrocarbon stream, which contained about 50 per cent propene, through conduit 57 and the expander and vaporizer 60. The vapors finally passing from the top of the fractionating column 50 through the conduit 61 contained about 70 per cent of C₃ hydrocarbons and about 6 per cent C₄ hydrocarbons, the remainder being lower-boiling material, including about 17 per cent of methane.

The charge to the polymerization step, which was separated from a low point of the fractionating column 50 through conduit 65, consisted primarily of C₃ and C₄ hydrocarbons, with only about 1 per cent of C₂ hydrocarbons, and contained substantially no methane or hydrogen. This stream had an appreciably higher ratio of C₃ to C₄ hydrocarbons than did the hydrocarbon stream entering the fractionating column through the conduit 46. The C₃ hydrocarbons which were vaporized and passed from the fractionating column 50 through the conduit 61 were recovered in subsequent parts of the separating apparatus and were finally brought back for inclusion in the polymerization charge stock by passing from separator 126 through conduit 127 as a liquid to separator 45 and thence, through conduit 46, to the fractionating column 50, so that the material passing through conduit 46 had a higher ratio of C₃ to C₄ hydrocarbons than did the effluent of the dehydrogenation.

The polymerization step was operated so as to polymerize substantially all of the C₄ olefin hydrocarbons, along with an appreciable portion of the C₃ olefins and the effluent of the polymerization was passed to the debutanizer 73. The polymers were separated therefrom and discharged to conduit 76. From the fractionating column, or debutanizer 73, the overhead vapors, which consisted primarily of C₃ and C₄ hydrocarbons, passed to the depropanizer 86 and therein a separation was made between the C₃ and C₄ hydrocarbons. The C₄ hydrocarbons passed from the bottom of the fractionating column through conduit 90 and were returned to the dehydrogenation step, while the C₃ hydrocarbons passed from the fractionating column 86 as vapors and were cooled and condensed in the cooler and condenser 98 and passed therefrom to the accumulator 52 from which they could again be withdrawn to be used as a refrigerant.

While in describing our invention we have illustrated it by the use of certain specific examples, it should be understood that we do not intend that it should be limited by the specific details so used. We have shown certain modifications of operation and also shown certain limits within which successful operation may be carried out, but various modifications will be apparent to those skilled in the art.

We claim:

1. A process which comprises passing a normally gaseous mixture containing butenes, propene, hydrogen and methane to a separating means, passing to said separating means propene vapors as subsequently recited, separating in said

- separating means a major portion of said hydrogen and methane, passing the residual mixture containing butenes and propene together with any residual minor proportion of unseparated hydrogen and methane in liquid phase to a fractional distillation means, withdrawing from said fractional distillation means a liquid polymerization feed stock consisting essentially of C₃ and C₄ hydrocarbons, including butenes and propene, the ratio of C₃ to C₄ hydrocarbons in said stock being substantially greater than that of the charge passed to said separating means, subjecting said feed stock withdrawn from said fractional distillation means to catalytic polymerization to effect polymerization of substantially all of said butenes and a substantial portion of said propene, subjecting the polymerization effluent to treatment to recover an essentially C₃ fraction of unreacted hydrocarbons containing propene.
2. A process as defined in claim 1, in which said heat-exchange relationship is direct heat exchange and in which said vaporized propene and uncondensed vapors from the fractional distillation means are passed together in a common stream to said separating means.
3. A process as defined in claim 1, in which said heat-exchange relationship is indirect heat exchange.
4. A process for producing normally liquid hydrocarbons by polymerization of propene and isobutene, which comprises passing into the middle section of a fractionating column in liquid phase a normally gaseous hydrocarbon mixture containing propene and isobutene and smaller amounts of lighter undesirable hydrocarbons, withdrawing from a low point in the column a liquid polymerization feed stock consisting essentially of C₃ and C₄ hydrocarbons, including propene and isobutene, that is substantially free from lighter hydrocarbons, the ratio of C₃ to C₄ hydrocarbons in said stock being substantially greater than that of the charge to said column, subjecting said feed stock to catalytic polymerization to effect polymerization of substantially all of said isobutene and a substantial portion of said propene, subjecting the polymerization effluent to separation to separate an essentially C₃ fraction of unreacted hydrocarbons containing the unreacted propene, liquefying at least a portion of said unreacted propene in said fraction, and discharging said liquefied unreacted propene into the top of said column in direct and intimate heat-exchange relationship with the vapors therein to act as a reflux and refrigerant therefor, allowing the unvaporized portion of said liquefied unreacted propene to descend said column and enter said polymerization feed stock, recovering the vaporized portion of said unreacted propene and introducing it to the middle section of said column in admixture with the feed thereto.
5. A process which comprises the thermal dehydrogenation of isobutane to form an effluent

containing isobutene, propene, hydrogen and methane, separating the major portion of said hydrogen and methane, charging the residual effluent in liquid phase into the middle section of a fractionating column, withdrawing from a low point in the column a liquid polymerization feed stock consisting essentially of C₃ and C₄ hydrocarbons, including propene and isobutene, that is substantially free from lighter materials, the ratio of C₃ to C₄ hydrocarbons in said stock being substantially greater than that of the charge to said column, subjecting said feed stock to catalytic polymerization to effect polymerization of substantially all of said isobutene and a substantial portion of said propene, subjecting the polymerization effluent to treatment to recover an essentially C₃ fraction of unreacted hydrocarbons containing the unreacted propene, liquefying at least a portion of said unreacted propene in said fraction, and discharging said liquefying unreacted propene into the top of said column in direct and intimate heat-exchange relationship with the vapors therein to act as a reflux and refrigerant therefor, allowing the unvaporized portion of said liquefied unreacted propene to descend said column and enter said polymerization feed stock, recovering the vaporized portion of said unreacted propene and introducing it to the feed stock to said column thereby to increase the C₃ to C₄ hydrocarbon ratio thereof over that of said residual effluent.

6. A process which comprises the thermal dehydrogenation of isobutane to form an effluent containing isobutene, propene, hydrogen and

methane, separating the major portion of said hydrogen and methane in a separating means, charging the residual effluent in liquid phase into the middle section of a fractionating column, withdrawing from a low point in the column a liquid polymerization feed stock consisting essentially of C₃ and C₄ hydrocarbons, including propene and isobutene, that is substantially free from lighter materials, the ratio of C₃ to C₄ hydrocarbons in said stock being substantially greater than that of the effluent from said dehydrogenation, subjecting said feed stock to catalytic polymerization to effect polymerization of substantially all of said isobutene and a substantial portion of said propene, subjecting the polymerization effluent to treatment to recover an essentially C₃ fraction of unreacted hydrocarbons containing the unreacted propene, liquefying at least a portion of said unreacted propene in said fraction, and passing said liquefied propene-containing fraction in indirect heat-exchange relationship with the vapors issuing from the fractionating column to allow the C₃ hydrocarbon fraction to expand and thereby act as a refrigerant for the vapors issuing from the fractionating column, thereby condensing substantially all of the C₄ fractions and at least a portion of the C₃ fractions in said vapors, returning condensed portions of the vapors to said fractionating column as a refluxing medium, and passing the expanded liquefied propene-containing fraction to the separating means.

CERTIFICATE OF CORRECTION.

Patent No. 2,351,123.

June 13, 1944.

HARRISON L. HAYS, ET AL.

It is hereby certified that error appears in the printed specification of the above numbered patent requiring correction as follows: Page 2, first column, line 58, for "isobutane" read --isobutene--; page 8, first column, line 21, claim 5, for "liquefying" read --liquefied--; and that the said Letters Patent should be read with this correction therein that the same may conform to the record of the case in the Patent Office.

Signed and sealed this 12th day of September, A. D. 1944.

Leslie Frazer
